UNITED STATES PATENT OFFICE

160,454

BABY TEETHER

George Azov and Solomon Tkatch,
San Francisco, Calif.

Application March 19, 1949, Serial No. 1,494

Term of patent 3½ years

(Cl. D83—1)

To all whom it may concern:

Be it known that we, George Azov and Solomon Tkatch, both citizens of no country, residing at 70 Barcelona St., city, and county of San Francisco, State of California, have invented a new, original, and ornamental Design for a Baby Teether, of which the following is a specification, reference being had to the accompanying drawing, forming part thereof in which

Fig. 1 is a front view of a baby teether, showing our new design; and

Fig. 2 is a side view of the same.

We claim:

The ornamental design for a baby teether, as shown.

GEORGE AZOV.
SOLOMON TKATCH.
